DEFLECTOR RING

Walker F. Peterson, Baltimore, Md.

Application January 14, 1941, Serial No. 374,398

6 Claims. (Cl. 137—111)

This invention relates to improvements in devices for quietly retarding the flow of liquids, and is particularly valuable in regulating stop valves for employment with automatic flushing valves.

In the Peterson and Walter Patents 2,089,223 and 2,089,224 have been shown constructions of such regulating stop valves in association with automatic flush valves. The rate of flow which can be regulated quietly through such valves for any given pressure differential is primarily dependent upon the dimensions of the structure itself, and secondarily upon the assembly alignment of the cooperating members, such as the inner conical member and the conical bore in the valve body. The commercially standard dimensions for making and mounting associated parts, and the consideration of external appearance, restrict the space allowance for such devices while the demands of economical commercial manufacture determine the accuracy which can be maintained. These factors establish a limit as to the rate of quiet flow which can be guaranteed for each of a number of such valves, although it is found in practice that greater rates of quiet flow can be employed with specially selected valves from such a group, or can be obtained at a greater expense by observing closer tolerances in manufacture and assembly.

It has been found that, for a given size of body, and for given operating conditions and tolerances of dimensions and assembly of parts, the rate of quiet flow can be materially increased by employing a discharge chamber construction including a member which primarily acts upon eddy currents in the chamber as distinguished from exercising a direct action upon the main flow stream from said cooperating members. Conversely, greater tolerances of dimensions and alignment of parts are permissible for a given rate of flow, when such a construction is employed.

An object of the present invention, therefore, is to provide a structure in which a greater rate of flow, without objectionable noise, can be secured with a given size of body and with a predetermined degree of accuracy in the construction and assembly of parts.

An illustrative form of practicing the invention in association with other members of the regulating stop valve assembly is shown in the accompanying drawing, in which:

Figure 1 is a coaxial sectional view through a regulated stop valve assembly.

Figure 2 is a corresponding view of the valve body structure alone.

Figure 3 is a sectional view substantially on line 3—3 of Fig. 2.

5 In the drawing, the illustrated valve has a body 10 with water supply connection 11 and the annular flange 12. Downstreamward of this flange, the interior of the body is provided with an enlarged bore 13 which preferably has the illustrated form of a truncated divergent cone having an apex angle of about 22 degrees the internal surface being formed with V-shaped ribs and grooves spaced forty to the inch. Beyond this bore is a collector chamber 14. A discharge connection 15 is provided with external threads 16 to receive the clamping nut 17 which presses the beveled end of the outlet tube 18 into the correspondingly shaped orifice of the discharge connection for providing a water-tight fitting. The 10 chamber 14 extends as a passage 19 which leads to the outlet tube 18, the walls of the passage 19 spreading outside of a continuation of the illustrated circular section (Fig. 3) of the chamber 14 itself, to provide a successively enlarging 25 channel for the movement of the liquid. The standardized dimensions of the structure are such that a part of the containing structure for the bore 13 is provided by a bridge wall 20 formed as a part of the body.

30 The adjusting and closing structure comprises a cap 25 which is threaded into the valve body and is apertured to receive the rotatable sleeve 26 having a collar 27 located in a cavity of the cap and secured therein by a split ring 28. A 35 sealing gasket 29 surrounds the sleeve 26 and is held in position by the gland nut 30. This sleeve 26 is threaded internally to receive the threaded stem 31 of the frusto-conical retarding member 32 which has the same apex angle as the bore 13 and has a similarly ribbed external surface. This member 32 carries a guide pin 34 which is slidable in a pocket 35 of the cone 32 and serves to prevent rotation of the member 32 when the sleeve 26 is turned, while permitting 45 a relative axial movement of the member 32. The smaller upstreamward end of the member 32 is provided with a seating washer 36 of fiber, lead, or like material for engaging the downstreamward surface of the flange 12 to provide a 50 stop against the passage of liquid, and to prevent injurious contact of the ribbed surfaces of the member 32 and the bore 13. The screw 37 holds the washer 36 in place.

According to the present invention, the collector chamber 14 is provided with a flow con-

trolling means which is illustrated as being a deflector ring 40 of larger internal diameter than the projection of the conical internal surface of bore 13, so that the sheet of water proceeding from the annular passageway between this bore 13 and the member 32 does not directly impact against it. It is preferably located nearer to the upstreamward end 38 of the collection chamber than to its downstreamward end 39. In the illustrated form, the deflector ring extends as a flange for 180 degrees about the chamber at the "blind side" or portion diametrically opposite the discharge connection 15, but may extend for a much greater or somewhat lesser peripheral distance. It is essential, for its functioning, that it extend continuously from the common plane through the axes of the discharge passage 15 and of the bore 13 for a distance of at least 40 degrees at the "blind side" denoted by bracket B on Fig. 3. In practice, it has been found that little advantage is gained by making the deflector ring longer than 180 degrees, i. e. 90 degrees from said common plane.

The character of the surfaces of the bore 13 and the member 32 may be varied as set out in the aforesaid patents.

The deflector ring may be either smooth, as by machining, or may be of the rough sand finish obtained in the usual casting for valves of this class.

A screw-driver can be engaged with the kerfed outer end of sleeve 26 as a tool for rotating the same and thereby moving the member 32 relative to the valve body. The annular spacing or clearance between these parts can thus be adjusted to secure the desired rate of flow for the prevailing mains pressure. With the present arrangement, very high rates can be obtained without causing noise to develop at normal pressures as employed for city water supplies. For instance, a rate of flow of 35 gallons per minute without objectionable noise can be obtained by soldering a deflector ring into the collector chamber of a valve assembly through which a similarly quiet flow of only 25 gallons per minute was previously possible under the same conditions of manufacturing tolerances and alignment of parts.

The axial thickness and the radial dimension of the deflector ring may be considerably varied, but it is preferred to have the axial thickness as small as commercially practicable for manufacture. The radial width of the deflector ring must be such that the inner part of this ring is substantially outside the path of the high velocity annular sheet; or, considered structurally, the deflector ring or flange is located external to the extension of the conical surface of the bore 13.

In studies of the behavior of water currents in such devices, it appears that a function of the deflector ring is to limit or control the water so as to change the character and direction of the eddy or back-flow currents from the high velocity discharge stream formed by the annular sheet, to render such currents of a character and amount that they do not operate to cause noise by interference with each other or with the main flow streams, to the end that the water in all parts of the collector chamber can quietly pass to the discharge connection.

As an example of commercial practice, the overall height of a valve body as shown in Figs. 2 and 3 was $2\frac{1}{32}$ inches; the interfitting threads in the cap 25 and body had a length of $\frac{3}{8}$ inch; the depth of the chamber 14 between surfaces 38 and 39 was $\frac{1}{32}$ inch; the cap threads were 1.75

inches outside diameter; the bore had a cylindrical portion $\frac{3}{2}$ inch in axial length for ease in machining, with a downstreamward divergent conical portion having a large diameter of 1.426 inches with a length of $\frac{3}{4}$ inch and an apex angle of 22 degrees; the distance from the body axis to the face of the outlet connection was $1\frac{1}{2}$ inches. The minimum radius of the collector chamber 14 was $6\frac{1}{64}$ inch, so that the radial distance from the large diameter of the bore 13 to the peripheral wall of the collection chamber (Fig. 2) was approximately $\frac{1}{4}$ inch. For this structure, the deflector ring was formed in the original casting, without machining of its surfaces, and extended 180 degrees as shown in Fig. 3, and had a thickness at its base of $\frac{3}{2}$ inch (a proper draft being provided at each side for casting), a height or radial width of $\frac{1}{8}$ inch, with rounded corners; it was spaced $1\frac{1}{64}$ inch from surface 38 and $1\frac{1}{64}$ inch from surface 39. A number of such devices all operated successfully with city water at pressures up to 100 pounds per square inch, and at flow rates of 32 gallons per minute or above.

It will be understood that the invention is not restricted to the particular form of employment shown, but that it may be modified in many ways within the scope of the appended claims.

I claim:

30. 1. A quiet flow retarding device for liquids comprising means for providing a collector chamber having a discharge connection and means for delivering a sheet of liquid across said chamber, and a flow controlling deflector means located in said chamber with a portion thereof diametrically opposite the discharge connection and extending toward but terminating short of the path of said sheet of liquid, said chamber including passages at both sides of said deflector means and extending in directions at acute angles to the path of said sheet and along which the liquid may flow directly into the discharge connection.
45. 2. A quiet flow retarding device for liquids comprising a body having a bore, an enlarged collector chamber downstreamward of said bore, and a lateral discharge connection; an internal member in said bore and cooperating therewith to restrict the flow of water to a thin annular sheet which is discharged into said collector chamber; and a deflector flange located on the wall of said collector chamber with a portion of the flange located diametrically opposite the discharge connection and other portions extending around the sheet toward the discharge connection substantially in a plane at acute angles to the direction of the sheet, said flange extending toward but terminating short of the path of said sheet of liquid.
60. 3. A quiet flow retarding device for liquids comprising a body having a bore, an enlarged collector chamber downstreamward of said bore and having a restricted length in the axial direction of the bore, and a lateral discharge passage from said chamber; an internal member in said bore and cooperating therewith to restrict the flow of water to a thin annular sheet which is discharged at high velocity into said collector chamber; means for closing the bore and having its inner surface spaced from the internal member; and flow controlling deflector means fixedly located within the chamber with a portion thereof located diametrically opposite the discharge passage external of but closely adjacent to the path of said high velocity sheet and extending

around the sheet substantially in the direction of a plane at right angles to the axis of the bore for a distance at the blind side of at least 40 degrees from each side of the common plane through the axes of the discharge passage and of the bore.

4. A quiet flow retarding device for liquids comprising a body having a bore, an enlarged collector chamber downstreamward of said bore and having a restricted length in the axial direction of the bore, and a lateral discharge passage from said chamber; an internal member in said bore and cooperating therewith to restrict the flow of water to a thin annular sheet which is discharged at high velocity into said collector chamber; means for closing the bore and having its inner surface spaced from the internal member; and flow controlling deflector means comprising a flange fixedly located within the chamber with a portion thereof diametrically opposite the discharge passage and external of but closely adjacent to the path of said high velocity sheet and extending substantially in the direction of a plane at right angles to the axis of the bore for a distance at the blind side of at least 40 degrees from each side of the common plane through the axes of the discharge connection and of the bore, said flange being located nearer the upstreamward end of the collector chamber than to the downstreamward end thereof.

5. A quiet flow retarding device for liquids comprising a body having a collector chamber therein with a discharge passage leading from said chamber, and an inlet including a wall extending into a part of the discharge passage, means in the inlet and cooperative therewith for delivering an annular sheet of liquid into the

chamber, said discharge passage being located at an angle to the direction of said sheet, an arcuate deflector flange located on the wall of said chamber opposite to the discharge passage and in a plane at right angles to the axis of the sheet, said deflector flange extending inwardly toward but terminating short of the path of said sheet of liquid and having a part located diametrically opposite the discharge passage and other parts extending along the chamber wall toward the discharge passage, said chamber including passages both upstreamward and downstreamward of said deflector flange and leading directly to the discharge passage in directions at right angles to the path of said sheet.

6. A quiet flow retarding device for liquids comprising a body having an inlet at one end and an enlarged collector chamber downstreamward of said inlet opening, a closing wall for said chamber at the opposite end of said body, a discharge passage leading laterally from said chamber, means at said inlet for delivering an annular sheet of liquid across said chamber toward said closing wall, and an arcuate deflector flange extending from the chamber wall toward but terminating short of the path of said sheet of liquid, said flange being located opposite the discharge passage and extending substantially in the direction of a plane at right angles to the axis of the sheet for distances of 40 to 90 degrees at each side of the common plane through the axis of said sheet and the axis of said discharge passage, said chamber including passages both upstreamward and downstreamward of said flange along which the liquid may flow directly toward the discharge passage.
